UNITED STATES PATENT OFFICE.

ISAAC H. MILLIKEN, OF ASPINWALL, PENNSYLVANIA, ASSIGNOR TO THE McCONWAY & TORLEY COMPANY, OF PITTSBURGH, PENNSYLVANIA, A CORPORATION OF PENNSYLVANIA.

WEAR-PLATE FOR CAR-COUPINGS.

1,344,184.

Specification of Letters Patent. Patented June 22, 1920.

Application filed March 21, 1918. Serial No. 223,771.

To all whom it may concern:

Be it known that I, ISAAC H. MILLIKEN, a citizen of the United States, residing at Aspinwall, in the county of Allegheny and 5 State of Pennsylvania, have invented certain new and useful Improvements in Wear-Plates for Car-Couplings; and I do hereby declare the following to be a full, clear, and exact description of the invention, such as 10 will enable others skilled in the art to which it appertains to make and use the same.

My invention relates to the construction of wear plates for interposition between a car coupler and its supporting carry-iron to prevent the coupler from being worn away by 15 the constant rubbing against the carry-iron to which it is subjected in service. The principal object of the invention is to produce a device of the character indicated 20 which readily lends itself to renewal when worn or if broken, and which may be detachably connected to the car coupler by interrelated structural parts without weakening the coupler or interfering with other 25 parts of the car equipment with which the coupler is associated. This object, generally stated, is attained by combining with the car coupler a wear plate provided with means detachably engaging the coupler to 30 prevent lateral movement of the plate with respect thereto, and having also means detachably engaging the coupler to restrain longitudinal movement of the plate relatively to the coupler.

35 In the drawings illustrating my invention, the scope whereof is pointed out in the claims,

Figure 1 is an inverted plan view of a construction embodying the invention.

40 Fig. 2 is a view, partly in side elevation and partly in section, illustrating the construction shown in Fig. 1, a supporting carry-iron being shown in section.

Fig. 3 is an inverted plan view of a modification of my invention.

Fig. 4 is a view, in side elevation of the construction illustrated in Fig. 3, a supporting carry-iron for the coupler being also shown.

50 Fig. 5 is an inverted plan view of another modified form of the invention.

Fig. 6 is a view, partly in side elevation and partly in vertical section, showing the construction illustrated in Fig. 5 supported 55 on a carry-iron.

The wear plates shown in Figs. 1, 2, 3 and

4 may be made of either forged or cast material; that illustrated in Figs. 5 and 6 is designed to be resilient so that it may be sprung into and out of interlocking relation 60 with the coupler.

In the drawings, 1 indicates the head of a car coupler and 2 is its stem. Except as hereinafter claimed these parts may be of any desired construction.

65 In the form of the invention illustrated in Figs. 1 and 2 the coupler is provided on its under side substantially at the junction of the coupler head 1 and stem 2 with a downwardly extending lug or projection 3 affording a rearwardly facing transversely-extending shoulder adapted to engage the corresponding transversely extending forward end 4 of a wear plate 5. At its rear end the wear plate is provided with a projection 70 6 which enters a recess or aperture 7 in the under side of the coupler. The projection 6 is preferably of hooked form, as shown, overlappingly engaging the coupler so as to support the rear end of the plate 5. The 75 opening 7 in the coupler stem is sufficiently elongated to allow the hooked projection 6 to enter; but the lateral walls of the opening preferably closely embrace the sides of the projection 6 so as to restrain lateral movement of the rear end of the wear plate with 80 respect to the coupler. When the parts are in assembled relation, lateral shifting of the forward end of the plate 5 with respect to the coupler is prevented by the engagement 85 90 of its transversely extending end 4 with the rear face of the projection or lug 3 on the coupler. Forward movement of the plate 5 upon the coupler stem is prevented by the engagement of the forward end of the plate 95 with the lug 3, while the engagement of the hooked projection 6 with the rear wall of the orifice 7 in the coupler stem prevents rearward movement of the plate with respect to the coupler. In service the wear plate 6 is 100 disposed between the under side of the coupler and the upper face of the carry-iron 8 by which the coupler is slidably supported.

105 The construction shown in Figs. 3 and 4 is an embodiment of the invention wherein the wear plate 9 is provided at its forward end with upwardly extending lugs 10 forming shoulders overlapping the respective sides of the coupler stem 2. The rear end of the wear plate 9 is preferably connected 110 to the stem 2 of the coupler by means of a hooked projection 6 that enters a recess 7 in

the coupler, as already described. As will be seen from Fig. 3, forward longitudinal shifting of the plate 9 with respect to the coupler stem is conveniently prevented by 5 the engagement of the forward end of the plate with the rear shoulders of the coupler head at the junction of said head and stem. The carry-iron upon which the plate 9 slides is indicated at 8 in Fig. 4.

10 The wear plate 11 illustrated in Figs. 5 and 6 is designed to be resilient so that, as shown in dotted lines at 11^a, it may be sprung into and out of assembled position. Like the other forms of construction it is 15 preferably provided at its rear end with a hooked projection 6 entering an orifice in the under side of the coupler stem. Its forward end is preferably provided with a tongue or projection 12 extending into a 20 corresponding rearwardly opening recess 13 formed in a transversely extending lug 14 that projects downwardly from the under surface of the coupler substantially at the junction of the coupler head 1 with the 25 coupler stem 2. The carry-iron 8 on which the plate 11 rests is shown in Fig. 6.

It is preferred that the abutting and contacting shoulders or faces of the wear plate and coupler shall fit closely against each 30 other, because the highest degree of efficiency in protecting the coupler from wear is attained when all movement of the wear plate with respect to the coupler is eliminated.

35 I claim:

1. In a device of the character indicated, the combination with a car coupler, of a

wear plate arranged on the under side thereof, and a carry-iron for supporting said wear plate and coupler, said coupler and wear plate having transversely extending engaging shoulders at one end of said wear plate and longitudinally extending engaging shoulders at the opposite end of said wear plate, and said wear plate engaging 40 said coupler and carry-iron only.

2. In a device of the character indicated, the combination with a car coupler having a head and stem, of a wear plate engaging the under side of said stem and having 45 shouldered engagement with said coupler substantially at the junction of said head and stem, the rear end of said wear plate having interlocking engagement with the coupler to thereby support said end of said plate against vertical movement.

3. In a device of the character indicated, the combination with a car coupler, of a carry-iron and a wear plate provided with 50 means detachably engaging the coupler for preventing lateral movement of the wear plate with respect to said coupler and provided with means detachably engaging the coupler for preventing longitudinal movement 55 of the wear plate with respect to the 60 coupler.

4. In a device of the character indicated, the combination with a car coupler, of a 65 resilient wear plate detachably mounted thereon, said wear plate and coupler having 70 interlocking portions adapted to be disengaged by flexing said plate.

In testimony whereof I affix my signature.

ISAAC H. MILLIKEN.
